Specification of Letters Patent.

Patented Feb. 21, 1922.

Application filed July 5, 1918. Serial No. 243,328.

To all whom it may concern:

Be it known that I, FREDERIC J. BRYANT, a citizen of the United States of America, residing at the borough of Manhattan, in the city, county, and State of New York, have invented certain new and useful Improvements in Ladders, of which the following is a specification, reference being had to the accompanying drawings.

This invention relates to improvements in ladders and particularly to improvements in ladders of the flexible type, i. e., ladders in which the rungs are supported by chains or the like so that the ladder may, if desired, be rolled into compact form for storage and readily unrolled for use; and an object of this invention is to provide a ladder in which the rungs will be large enough in diameter to afford to the user a good hand-grasp or hand-hold and, at the same time, to provide a ladder which will combine lightness with strength. Other features and objects of this invention may be enumerated as follows: (1) The provision of safe and durable means by which the rung may be secured to the suspensory members; (2) The provision of a wooden rung and means by which the same is kept from cracking and splitting at the point where it engages the suspensory member; (3) The provision of means whereby the rung is strengthened against the load stress at the point where it engages the suspensory member; (4) The provision of means by which the rung is safeguarded against wear where the rung is attached to the suspensory member; (5) The provision of means for preventing the slipping of the suspensory member along the rung, either from off the rung or towards the center thereof; (6) The provision of simple and strong means for holding the ladder from the wall of the building or vessel from which the ladder is hung; (7) The provision of means by which it is practicable to use larger and stronger rungs with flexible suspensory members; and (8) The provision of means whereby a chain-link (or the like) of the suspensory member is safeguarded against distortion or rupture due to the drawing thereagainst of a ring or anchor. Other features of this invention will be pointed out in the description that follows hereinafter.

In the drawings illustrating the principle of this invention and the best mode now known to me of applying that principle, Figure 1 illustrates the ladder set up for use;

Figure 2 is a section on the line A—A of Figure 1; Figure 3 is a detail of an end of the wooden rung; Figure 4 is a section on the line B—B of Figure 3; Figure 5 illustrates a modified form of the wooden rung-end; Figure 6 is a section on the line C—C of Figure 5; Figure 7 is a detail of one of the armor-rings used on the rung-end shown in Figures 6 and 7; Figure 8 shows a grooved band or ferrule substituted for the pair of rings as rung-end armor; Figure 9 illustrates the manner of mounting a distance-preserving disk on the rung-end; Figures 10 and 11 show a modified form of attachment of the chain to the rung-end; Figure 12 illustrates the attachment of the chain to a slotted, armored rung-end; Figure 13 is a section on the line D—D of Figure 12; Figure 14 illustrates a modified form of rung reinforcement; and Figure 15 is a detail showing a thimble reinforcement of a link.

As is shown in Figure 1, the suspensory members that form the sides of the ladder X and support the rungs a, b, at the ends thereof are illustrated as chains c through the upper end-links d of which pass rings e that are fastened to the beam or sill f by means of the lashings or cords g; of course, any other suitable means of securing the ladder X to the building, vessel or other structure may be used without departing from the spirit of this invention. Where it is feasible to do so, the lower end-links h may be attached to a holdfast i lying in or on the floor or ground or floating on the water, through the medium of the turn-buckles j and rings k, for example; and by adjusting the turn-buckles j the tautness of the suspensory side-supports c may be advanced, as may be desired.

As illustrated in Figure 1, I provide wooden rungs a. Wood being lighter than metal, the wooden rungs a may be made of comparatively larger diameter than that of the metal rungs for the same purpose, whereby the user of the ladder is enabled to grasp the wooden rung a more firmly and the latter will afford him a firmer or more secure foothold, moreover. However, it has been found that difficulty attends the attachment of wooden rungs to chain side-supports or suspensory members of a like nature and that a wooden rung is likely to split or crack, as well as to wear at or near the point of application of the load stress, by reason of the constant rubbing of

the chain-links that adjoin the end of the rung a . To avoid such splitting, cracking and wearing away of the latter and to provide a simple, durable and efficient means of 5 attaching the ends of the wooden rung a to the chain side-supports c , the following arrangement of parts is provided: The end a' of the wooden rung a is reduced in diameter, whereby there is formed a 10 shoulder a'' against which there is forced a metal ring m that lies in a substantially vertical plane (figures 4 and 3). Over the reduced end a' , there is next slipped the link n of the chain c ; this link n may be larger 15 than the intermediate links o and it may be larger in its original size or it may be enlarged (as by opening or spreading) from the normal size of the chain-links o . Next there is slipped over the reduced end a' 20 an outer wear-ring m' , which may be substantially the same in size and character as the ring m that serves as a wear-ring or abutment for the link n . A washer p is then put over the end face of the rung a 25 and is held in place by means of a screw q that passes lengthwise of the rung a therewith and, what is an important feature, to a point inward of the rung that lies beyond the point of application of the load stress a 30 substantial distance. As is clearly shown in Figures 5 to 7, both inclusive, the reduced end a'' of the rung a may be formed with flattened sides a^* (Figure 6), whereby the rung-end a'' is given such a shape that it will 35 readily fit into a link o of the normal size and shape, i. e., the size and shape of the links that make up the main part of the chain c . This dispenses with the necessity of having larger-sized links n ; i. e., instead 40 of shaping the link to fit the rung-end, the rung-end is shaped to fit the normal size of link o . The wear-ring r and outer wear-ring r' (Figure 7) likewise have flattened sides r'' , so that they fit snugly the reduced 45 end a'' of the rung a . As in the construction illustrated in Figures 4 and 3, the wear-ring r' and the chain-link o are held against outward shifting from off the rung-end a'' by means of the washer p and the screw q . 50 The rings m , m' , may be replaced by a single element in the form of a collar or ferrule; thus as is illustrated in Figure 9, there is slipped on the rung-end a' a collar or band s formed with a circumferential 55 groove s' within which is mounted the link s'' of the chain c . The collar is held against end-wise displacement from off the rung-end a' by means of a washer p and screw q . Where it is desired to provide the rung a 60 with disks by means of which the ladder X is held away from the side of the building, vessel or other structure, the disk t may first be slipped upon the rung-end a' , until the disk rests against the shoulder a'' (Figure 65 9), whereupon the collar s is passed over

the rung-end a' and the whole held in place by the washer p and the screw q . Of course, the disk t may be used to serve the purpose of the wear-rings m , r , (Figures 3 and 7) and in place thereof in the structures 70 illustrated the figures just named. Instead of using the washer p and the screw q as means for retaining the rings m , m' , (or the rings r , r') and the link n (or the link o) in place, there may be used a U-shaped retaining clip u (Figures 11 and 10) the bottom of which rests against the end-face of the rung-end a' and the arms u' of which embrace the rung a and are secured thereto by means of the rivet u'' . 75

As is clearly shown in Figures 12 and 13, the rung-end v' of the rung v differs from the rung-end a' of the rung a in that the rung-end v' is split, i. e., formed with the slot v'' which is adapted to receive the 85 chain-link o . As in the construction illustrated in Figures 11 and 10, there are provided an inner wear-ring m and an outer wear-ring m' between which lies the link o ; and the U-shaped clip u and the rivet u'' (or like fastening device) is provided to hold the link o and the outer wear-ring m' in place. In Figure 14, there is illustrated a wooden rung w which is hollow, i. e., formed with a central passage w' that extends from end to end of the rung w ; and, through this passage w' , there is passed a bolt w'' having a head w^* , between which and the end of the rung w , there is held the link o of the chain c . On the opposite end of the bolt w'' , there is screwed a nut x , between which and the other end of the rung w , there lies a link o of the other rung-supporting member c . 90

It is to be observed that the rings m , m' , the collars s and the rings r , r' , serve to strengthen, in a material degree, the rung-ends upon which they are mounted and to prevent splitting and cracking of the same. Not only do they perform this function directly by reinforcement of the rung-ends (which, it is to be borne in mind, are reduced) but they operate or act indirectly by preserving the rung-ends from wear due to the constant rubbing of the chain-links connected to the ones mounted on the rung-ends. It is to be observed that the main or body-portion of the rung a (which is of wood) may be made of a comparatively large diameter without unduly increasing the weight 110 of the ladder X as a whole, whereby the user is afforded a safe handhold (safe because it may be grasped more firmly than can a rung of small diameter), as well as a secure foothold. In the construction shown 115 in Figure 14, the wooden rung w is strengthened against breaking under a load by the passage therethrough of the bolt w'' . In Fig. 1 there are shown means to prevent stripping of the chains from the upper- 120 125 130

most rung *b*, in case the lashing *g* or other anchorage means should break loose at one side while the ladder is in use, and thus impose a sudden shock and severe strain upon

5 the other chain. These means comprise a disk *3* mounted at each end of the rung *b* and held thereon by a nut *4*, which is secured in place as by upsetting the end *2'* of the rung against said nut. Also in this structure the links *o* which engage the ends of rung *b* are fitted in grooves *6* provided on clips *5* that fit over the rung ends, to thus provide localizing seats for said links *o*.

To strengthen the links *d* through which 15 pass the rings *e*, these links *d* are fitted with interior thimbles *7* which reinforce the links *d* and prevent rupture or distortion of the same (Figure 15).

Since the ladder must be adapted to be 20 stored in small compass, the rung-supporting members must be flexible, which requirement is met in the ladder *X* by the chains *c*. Since the ladder must be adapted for use in emergencies the exigencies or circumstances 25 of which may demand that the ladder be handled by a single person (e. g., a hotel guest), the ladder must be light; but, obviously, it must be reliable and safe in operation and use. Therefore, the ladder must

30 combine with lightness, great strength. Moreover, the ladder must be such as will afford a safe means of descent to persons of all ages and both sexes, and particularly to persons unused to descending ladders. Furthermore, it is to be borne in mind that the 35 descent being made under emergency conditions, will doubtless and inevitably be attended by excitement and haste. Strength is obtained (1) by using chains *c* of steel 40 having high tensile resistance; (2) by reinforcing the upper end-links *d* by means of thimbles *7*; (3) by reinforcing the rung-ends *a'* by means of the metal bands *m*, *m'*, *r*, *r'*, *s*, which not only add strength to the 45 rung-ends but prevent weakening the same by serving as armor therefor to avoid wear due to rubbing of the chain-links *o* that are just below the rung-ends *a'*; (4) by adding within the rung-ends *a'* the screws *q* that are 50 so long as to extend lengthwise of the rung to a point beyond the point of application of the load stress. As has been explained, for the screws *q* may be substituted a bolt *w'* that passes entirely through the rung (see 55 the rung *w*, Figure 14). The requisite strength combined with lightness is attained by the use of chains *c*, the links *o* of which between the links *n* that receive the rung-ends *a'* are more closed than the latter links

60 *n* and by the use of rungs *a* of wood or its well-known equivalents. To the frightened and inexperienced user of the ladder under the trying circumstances of an emergency, there are furnished a sure handhold and a 65 foot-hold by reason of the fact that the di-

ameter of the wooden rung *a* may be made of large dimension without occasioning an excessive increase in the weight of the ladder as a whole.

Those of the links which are to receive the diminished rung ends *a'* (see Fig. 4) are indicated by the reference character *n*, and, as there represented, have their side bars bulged or expanded in substantially the pre-formed structure at *n'*, in order that these particular links may have a sufficiently large opening to permit the reception therein of the diminished rung end, without necessitating such a considerable reduction of the rung ends as would tend to weaken the latter. The opened or spread link *n* is not, perhaps, so resisting as is its normal form *o*; but collapse or approach of its sides *n'* is prevented by the insertion of the armored and reinforced rung-end *a'*. I consider this change of form of the link to be an important feature of this invention.

Variations within the spirit and scope of my invention as claimed are equally comprehended herein.

90

I claim:

1. A flexible ladder comprising a pair of chains, non-metallic rungs of light weight material having hand-hold portions of relatively large diameter and reduced ends to engage in opposite links of said chains, and means for effecting rigid joints between said rung ends and their engaging links.

2. A flexible ladder comprising a pair of chains, wooden rungs having hand-hold portions of relatively large diameter and reduced ends to engage in opposite links of said chains, and means for effecting rigid joints between said rung ends and their engaging links.

3. A flexible ladder comprising a pair of chains and non-metallic rungs of light weight material having hand-hold portions of relatively large diameter and reduced ends to engage non-rotatably in opposite links of said chains.

4. A flexible ladder comprising a pair of chains and non-metallic rungs of light weight material having hand-hold portions of relatively large diameter and reduced, non-circular ends to engage non-rotatably in opposite links of said chains.

5. A flexible ladder composed of parallel chains, non-metallic rungs of light weight material having hand-hold portions of relatively large diameter and reduced ends to engage in opposite links of said chains, and means for effecting rigid joints between said rung ends and their engaging links.

6. A flexible ladder comprising a pair of continuous chains, non-metallic rungs of light weight material having hand-hold portions of relatively large diameter and reduced ends to engage in opposite links of said chains, and means for effecting rigid

1. joints between said rung ends and their engaging links.
2. A flexible ladder comprising a pair of continuous chains and non-metallic rungs of light weight material having hand-hold portions of relatively large diameter and reduced ends to non-rotatably engage in opposite links of said chains.
3. A flexible ladder comprising a pair of continuous chains, and non-metallic rungs of light weight material having hand-hold portions of relatively large diameter and reduced, non-circular ends to engage non-rotatably in opposite links of said chains.
4. A flexible ladder comprising a pair of chains whose links are relatively narrow to be capable of sliding easily over obstructions, wooden rungs having hand-hold portions of relatively large diameter and reduced ends to engage in opposite links of said chains, and means for effecting rigid joints between said rung ends and their engaging links.
5. A flexible ladder composed of parallel chains whose links are relatively narrow to be capable of sliding easily over obstructions, wooden rungs having hand-hold portions of relatively large diameter and reduced ends to engage in opposite links of said chains, and means for effecting rigid joints between said rung ends and their engaging links.
6. A flexible ladder comprising a pair of continuous chains whose links are relatively narrow to be capable of sliding easily over obstructions, wooden rungs having hand-hold portions of relatively large diameter and reduced ends to engage in opposite links of said chains, and means for effecting rigid joints between said rung ends and their engaging links.
7. A flexible ladder comprising a pair of chains, non-metallic rungs of light weight material having hand-hold portions of relatively large diameter and reduced ends to engage in opposite links of said chains, means for effecting rigid joints between said rung ends and their engaging links, and metallic reinforcing means axially penetrating said reduced ends and extended into the diametrically large portions of said rungs.
8. A flexible ladder comprising a pair of chains, non-metallic rungs of light weight material having hand-hold portions of relatively large diameter and reduced ends to engage in opposite links of said chains, means for effecting rigid joints between said rung ends and their engaging links, and end securing means to maintain the connective relation between said rung ends and their engaging links.
9. A flexible ladder comprising a pair of chains, non-metallic rungs of light weight material having hand-hold portions of relatively large diameter and reduced ends to engage in opposite links of said chains, means for effecting rigid joints between said rung ends and their engaging links, rings upon said rung ends flanking said engaging links, washers at the rung ends to prevent endwise displacement of said rings and engaging links, and reinforcing screws axially penetrating said rung ends and extending into the diametrically large rung portions, said screws also serving to secure said washers to the rung ends.
10. A flexible ladder comprising a pair of chains, non-metallic rungs of light weight material having hand-hold portions of relatively large diameter and reduced ends to engage in opposite links of said chains, means for effecting rigid joints between said rung ends and their engaging links, and means for preventing wear upon the rung ends by the rubbing action of links adjacent the rung engaging links.
11. A flexible ladder comprising a pair of chains, non-metallic rungs of light weight material having hand-hold portions of relatively large diameter and reduced ends to engage in opposite links of said chains, means for effecting rigid joints between said rung ends and their engaging links, and rings upon said rung ends to prevent wear of the latter through the rubbing action of links adjacent the rung engaging links.
12. A flexible ladder comprising a pair of chains, non-metallic rungs of light weight material having hand-hold portions of relatively large diameter and reduced ends to engage in opposite links of said chains, means for effecting rigid joints between said rung ends and their engaging links, ladder distancing disks carried by some of said rungs, and securing means to prevent endwise displacement of said engaging links and distancing disks from said rung ends.
13. A flexible ladder comprising a pair of chains, non-metallic rungs of light weight material having hand-hold portions of relatively large diameter and reduced ends to engage in opposite links of said chains, means for effecting rigid joints between said rung ends and their engaging links, and rings upon said rung ends to prevent wear of the latter through the rubbing action of links adjacent the rung engaging links.
14. A flexible ladder comprising a pair of chains, non-metallic rungs of light weight
- material having hand-hold portions of relatively large diameter and reduced ends to engage in opposite links of said chains, said engaging links being expanded for the reception of said rung ends, and means for effecting rigid joints between said rung ends and their engaging links.
15. A flexible ladder comprising a pair of chains, whose links are relatively narrow, non-metallic rungs of light weight material having hand-hold portions of relatively large diameter and reduced ends to engage in opposite links of said chains, means for effecting rigid joints between said rung ends and their engaging links, and metallic reinforcing means axially penetrating said reduced ends and extended into the diametrically large portions of said rungs.
16. A flexible ladder comprising a pair of chains, non-metallic rungs of light weight material having hand-hold portions of relatively large diameter and reduced ends to engage in opposite links of said chains, means for effecting rigid joints between said rung ends and their engaging links, and end securing means to maintain the connective relation between said rung ends and their engaging links.
17. A flexible ladder comprising a pair of chains, non-metallic rungs of light weight material having hand-hold portions of relatively large diameter and reduced ends to engage in opposite links of said chains, means for effecting rigid joints between said rung ends and their engaging links, rings upon said rung ends flanking said engaging links, washers at the rung ends to prevent endwise displacement of said rings and engaging links, and reinforcing screws axially penetrating said rung ends and extending into the diametrically large rung portions, said screws also serving to secure said washers to the rung ends.
18. A flexible ladder comprising a pair of chains, non-metallic rungs of light weight material having hand-hold portions of relatively large diameter and reduced ends to engage in opposite links of said chains, means for effecting rigid joints between said rung ends and their engaging links, ladder distancing disks carried by some of said rungs, and securing means to prevent endwise displacement of said engaging links and distancing disks from said rung ends.
- Signed at the borough of Manhattan, city, county and State of New York, this first day of July, 1918, in the presence of the two undersigned witnesses.
